Primary Examiner — Bridget L Eland(74) Attorney, Agent, or Firm — Panasonic Patent Center(57) CLAIM

We claim the ornamental design for a video camera case, as shown and described.

DESCRIPTION

FIG. 1 is a front view of a video camera case of the present invention;

FIG. 2 is a rear view thereof;

FIG. 3 is a top view thereof;

FIG. 4 is a bottom view thereof;

FIG. 5 is a first side view thereof; and,

FIG. 6 is a second side view thereof.

The broken line showing of video camera case is included for the purpose of illustrating environment and forms no part of the claimed design.
